UNITED STATES PATENT OFFICE.

BENJAMIN ALFRED DOBSON AND WILLIAM ISHERWOOD BROMILEY, OF BOLTON, ENGLAND, ASSIGNORS TO DOBSON & BARLOW, OF SAME PLACE.

TRAVELING-FLAT CARDING-ENGINE.

SPECIFICATION forming part of Letters Patent No. 452,993, dated May 26, 1891.

Application filed October 23, 1890. Serial No. 369,139. (No model.) Patented in England December 5, 1889, No. 19,519.

To all whom it may concern:

Be it known that we, BENJAMIN ALFRED DOBSON and WILLIAM ISHERWOOD BROMILEY, subjects of the Queen of Great Britain, 5 residing at Bolton, in the county of Lancaster, England, have invented certain new and useful Improvements in Traveling-Flat Carding-Engines, (for which we have obtained Letters Patent in Great Britain, No. 19,519, and 10 bearing date December 5, 1889,) of which the following is a specification.

Our invention relates to improvements in grinding the wire-clothing of those flats of carding-engines which are known as "revolving" or "traveling" flats, and has for its object 15 to grind the flats efficiently when relatively in the same position as that which they occupy when performing their work upon the cylinder—*i. e.*, wire downward—and thereby 20 to avoid the irregularity or inexactness due to the deflection of the flats, which sometimes results when the flats are ground with the wire upward. We are aware that this has 25 previously been done, but not in the same manner as that in which we now perform it.

In order that our invention may be fully understood and readily carried into effect, we will describe the accompanying three sheets 30 of drawings, reference being had to the letters marked thereon.

Figure 1 is a side elevation of part of the chain of traveling flats of a carding-engine, illustrating the application of our improvements in means for grinding the same. Fig. 35 2 is an end view of the devices shown in Fig. 1. Figs. 3, 5, 7, and 8 are side elevations of alternative arrangements for regulating the position of the slide upon which the reversed flats are supported while being ground. Figs. 40 4 and 6 are end views of the devices shown in Figs. 3 and 5, respectively. Figs. 7^a and 7^b are two detail views of part of the devices shown in Figs. 7 and 8, respectively. Figs. 8^a and 8^b are respectively a side elevation 45 and an end view, partly in section, of an arrangement of parts whereby the grinding-roller is moved toward and from the flats being ground. Figs. 9 and 10 are views of two arrangements for pressing the flats upward 50 while being ground. Figs. 11, 12, 13, and 14

are detail views, on an enlarged scale, illustrating the section of the flat and the manner of mounting the same according to our invention. Fig. 15 is a view showing the application of the carriage for supporting the 55 grinding-roller, and Fig. 16 is a view of the carriage on a larger scale.

The drawings show one side only of the carding-engine; but it will of course be understood that certain of the parts which necessarily go to make up a complete operative machine will be duplicated upon the side not shown in the drawings.

Similar letters refer to similar parts throughout the several views.

In carrying out our improvements we alter the section of the flat *a* in such a way—that is, by making it with two shallow ribs in place of one deep one, as is usual, as shown best in Figs. 13 and 14—that while retaining the 70 necessary strength to resist deflection it can be arranged to pivot or turn over on the studs *b*, by which it is attached to the chain-links *c*, connecting the flats *a* together, and by means of which they are driven in the ordinary manner, each flat being able to turn over on its studs *b*, as described, without touching either of the flats adjoining it.

Secured to the engine-bend is a flat grinding-bracket *d*, in slideways in which is fitted a slide *e*, the upper surface of which is made straight to receive each flat *a* after it has been automatically reversed by means of a catch *f* or an equivalent thereof coming against lugs on the flats, as shown in Fig. 1. 85 As the reversed flats are carried along the straight portion of the slide *e* on their working-surface we pass them over a grinding apparatus designed for the purpose of grinding flats from the "working-surface"—*i. e.*, that 90 part upon which the flat is supported on the flexible bend when carding, or by means of pivoted levers *h*, Fig. 9, acted upon by the springs *g* or weights *h'*, Fig. 10, we may press each flat *a* upward (see Fig. 10) against the 95 grinding-surface *s*, which is reversed in position, and grind in the ordinary manner with the flat reversed.

In the ordinary mode of grinding, the back of the flat *a* would rest upon the upper side 100

of the plate or grinding-surface *s*, and the grinding-roller *i*, placed above the plate *s*, would act upon the teeth of the flat, where-
 as when we use the ordinary grinding-surface
 5 or plate *s* the back of the flat, wire down-
 ward, is pressed against the underside of said
 plate and the grinding-roller *i* is placed be-
 low. The grinding-roller *i* therefore works
 10 between the flats *a*, which are supported on
 the flexible bend or equivalent *j* and work-
 ing on the cylinder and those above return-
 ing from work, and it is these flats returning
 from work that we turn over, as shown in
 15 Fig. 1, and grind after they have been stripped
 and, if necessary, brushed.

We desire to point out that according to our invention the center of gravity of each reversed flat is such that it will, when liber-
 ated, return to its normal position with the
 20 wire upward without the help of the catch *f'*
 and lugs or other means, which are, however,
 provided in order to prevent any accident.
 This is effected by causing the studs *b* to enter
 25 the flats lower down than usual, so that,
 the weight of the flat above *b* being greater
 than the weight below, the flats will, if left to
 themselves, always turn upon the studs *b* into
 30 the position described with the wire upward,
 and consequently when the flats come onto
 the flexible bend *j* they will be in their proper
 working positions with the wire downward.

With regard to the grinding arrangement shown in Figs. 1 to 10, the grinding-roller *i* is simply mounted in bearings in the grinding-
 35 roller bracket *d* and has nothing particular
 about it or anything in its nature of opera-
 tion differing from that of an ordinary grind-
 ing-roller for the purpose of grinding flats.

t, Figs. 1 and 2, is a roller so mounted in
 40 its supports as to have a certain amount of
 vertical play or movement and serving as a
 weight to bear down on and hold the flats
 upon the straight portion of the slide *e*. The
 grinding-roller is supported in brackets or
 45 bearings in substantially the usual manner;
 but as the flats are reversed before being
 ground this roller must necessarily work be-
 tween instead of above the chain of flats, and
 consequently the roller must be placed in po-
 50 sition or removed from the side of the ma-
 chine rather than from above.

For the purpose of passing the grinding-
 roller *i* from one side of the carding-engine
 to the other between the chain of flats with-
 55 out any risk of damage to either the ordinary
 tightening-rollers, (indicated at *u* in dotted
 lines, Fig. 15,) which are mounted upon the
 shaft *m* and are used to take up the slack in
 the chain of flats or to the flats themselves,
 60 we provide a carriage, Figs. 15 and 16, which
 consists, preferably, of two parts *k* *k'*, con-
 nected together by a slide. The part *k* is
 provided with a bowl *l* to run on the top of
 the cross-shaft *m*, connecting the tightening-
 65 bowls *u* for the flat-chain *c*, and the other
 part *k'*, which is formed with a cradle *k*
 to carry one end of the grinding-roller *i*,

runs with flanged bowls *n* upon a shaft *o*,
 which we place across the card from one tight-
 ening-fixing to the other, and which also acts
 70 as a stay. It will be readily understood that
 this carriage is removable, only requiring to
 be lifted off the shafts *m* and *o*.

As all traveling-flat carding-engines have
 the tightening-rollers and the shaft *m*, on
 75 which they are mounted adjustably, it is
 thought that it is not necessary to show the
 means for making such adjustment. It is
 this adjustability of the shaft *m* which neces-
 sitates the carriage being made in the two
 80 parts *k* and *k'*, as has been described.

In using this carriage it is moved to one
 side of the carding-engine, and the workman
 rests one end of the roller *i* upon the cradle
 85 *k*² and then pushes the roller and carriage
 across the machine, when two workmen, one
 at each end of the roller, can easily lift it into
 its bearings.

It will be understood that the arrangement
 just described is not an alternative arrange-
 ment from that shown for grinding the flats,
 but that the carriage *k* *k'* is a simple device
 90 for passing the grinding-roller *i* from the side
 of the carding-engine between the two sec-
 tions or parts of the chain of flats across and
 95 into its position—that is, into its bearings
 in the brackets *d*. The reason for making
 the carriage *k*² in two parts is to permit the
 two rollers *l* and *u*, which are carried, respect-
 100ively, by the said parts, to always run upon
 the shafts *m* and *o* whether they be close to-
 gether or farther apart.

In order to utilize the apparatus for grind-
 ing from the working-surface of the flats at
 present in use, we should require to travel
 105 the flats in the reverse direction to that now
 customary, so that the cleaned flats would en-
 ter to work on the cylinder at the doffer in-
 stead of at the licker-in end; but this method
 110 of traveling flats is generally considered ob-
 jectionable, and in order to grind from the
 working-surface with the flat in the reversed
 position while traveling in the ordinary di-
 115 rection we have devised means by which this
 can be done.

Referring first to Figs. 3 and 4, in the mov-
 able slide *e* (on each side of the carding-en-
 gine) is a slot in which is closely fitted an
 eccentric *p*, from which there is a projecting
 120 finger or bracket *p'*. The action is such that
 as the flats travel forward after having been
 reversed in position the screwed studs *b*, upon
 which the links of the flat chain *c* work, and
 each of which is prolonged to form a head by
 125 which the stud may be screwed up, come into
 contact with the finger or bracket *p'*, attached
 to the eccentric *p*. This finger or bracket *p'*
 should be so shaped as to project over the
 path of the head of the stud *b*, whereby the
 130 finger or bracket *p'* is lifted and turns the
 eccentric *p* and raises the slide *e*, and after it
 passes from engagement therewith allows it
 to fall by its own weight and those of the
 flats bearing upon it during the passage of a

reversed flat over the grinding-roller *i* in such a manner that the surface of the wire of the flat immediately over the center line of the grinding-roller is always maintained at the same distance from the surface of the grinding-roller. In other words, this movement of the eccentric *p* and slide *e* will counteract or compensate the inclination given to the flat and generally known as "heel" or "bevel." The bevel on the flat is the incline always cut on that surface of each flat which travels on the flexible bend, and it is necessary to employ a device such as the eccentric *p* and finger *p'* and slide *e* to compensate for this inclination and keep the wire on the flat in its proper position relatively to the grinding-roller.

In Figs. 1 and 2 the end of the eccentric finger *p'* is shown resting upon the lower flats working upon the flexible bend or equivalent *j*. In Fig. 7 the eccentric *p* is dispensed with and the finger *p'* is made in two pieces adjustably connected by a nut and bolt *x*, passing through the two parts of the finger, one of which is slotted, (see Fig. 7^a), so that the length of the finger can be varied, if required. Instead of the eccentric *p*, the finger *p'* is pivoted at *p''*, and an extension-arm *p'''* is employed to raise and lower the slide *e*. In Figs. 5 and 6 an alternative arrangement is also shown, the finger *p'* being pivoted at *p''* to the bracket *d*, and the arm *p'''* actuating the slide *e*. In this construction, as well as those shown in Figs. 7 and 8, the finger *p'* is actuated by the chain of flats passing under it, and the arm *p'''* engages with and raises the slide *e* as the arm *p'* is rocked. The contact part *p⁴*, Fig. 8, which lies on the back of the flats, can be adjusted by means of a screw *p⁵*, so as to compensate for any stretching or wear in the links of the flat chain.

In Fig. 8 the flats slide upon a rocking frame *q*, pivoted at *r*. This frame replaces the slide *e* and is lifted and lowered at one end by an eccentric or the arm *p'''*.

Either of the arrangements herein shown and described might be employed to raise and lower the grinding-roller *i* (see Figs. 8^a and 8^b) while the reversed flats were passing over a fixed guide in place of the slide *e*. The grinding-roller in this case is mounted in bearings *d'*, arranged to slide vertically in the bracket *d*.

What we claim is—

1. In a carding-engine, the combination of a chain of traveling flats and a grinding-roller arranged between the upper and lower flats of the chain to grind said flats when reversed, substantially as described.

2. A chain of flats for carding-engines, consisting of the links *c* and independently-reversible flats journaled at their ends to the said links by studs, substantially as described.

3. In combination, in a carding-engine, a grinding-roller supported in brackets above

the engine-bend and a traveling chain of flats inclosing the roller and consisting of links *c* and independently-reversible flats connected at their ends to the links by studs, whereby each flat may be reversed independently to present its wires to the roller as it passes above the same, substantially as described.

4. In a carding-engine, the combination of a grinding-roller supported above the engine-bend, and a chain of traveling flats, each flat being pivotally supported by the links of the chain, whereby it is free to be reversed, and the said pivots being arranged eccentrically of the flat, whereby when free the said flat will automatically turn to its normal or working position, substantially as set forth.

5. The combination, in a carding-engine, of a chain of traveling flats, a grinding-roller supported within the chain, a slide or frame to guide the flats, a finger adapted to be moved by the traverse of the flats, and an eccentric projection connected with the said finger and operatively connected, substantially as described, to regulate the position of the roller and frame with relation to each other for the purpose of compensating for the heel or bevel in a flat being ground in a reversed position, substantially as described.

6. In combination with a flat-grinding mechanism for carding-engines, a carriage adapted to support the grinding-roller as it is being moved to or from its place on its supporting-bearings, the said carriage being mounted upon supports upon which it is free to be moved from side to side of the card, substantially as set forth.

7. In a carding-engine, the combination of a chain of traveling flats and a grinding-roller supported below the upper flats of the chain, substantially as described.

8. In a carding-engine, the combination of a chain of traveling flats, a grinding-roller supported below the upper flats of the chain, and a slide or frame to present the reversed flats in proper relation to the grinding-roller, substantially as described.

9. In a carding-engine, the combination of a chain of traveling flats, a grinding-roller supported below the upper flats of the chain, a slide or frame to present the reversed flats in proper relation to the roller, and means for regulating the relative positions of the guiding-surface of the slide and the surface of the roller, substantially as described.

10. In a carding-engine, the combination of a chain of traveling flats, a grinding-roller supported below the upper flats of the chain, and a movable slide or frame to present the reversed flats in proper relation to the roller, substantially as described.

11. In a carding-engine, the combination of a chain of traveling flats, a grinding-roller supported below the upper flats of the chain, a slide or frame to present the reversed flats in proper relation to the roller, and mechanism for automatically regulating the relative

positions of the guiding-surface of the slide and the surface of the roller, substantially as described.

12. In a carding-engine, the combination of 5 a chain of traveling flats, a grinding-roller supported below the upper flats of the chain, a slide or frame to present the reversed flats to the roller at an angle, and a lever automatically regulating the relative positions of 10 the slide or frame and the surface of the roller, substantially as described.

13. In a carding-engine, the combination of 15 a chain of traveling flats, a grinding-roller supported below the upper flats of the chain, a slide or frame to present the flats to the roller at an angle, and a lever operated by the traveling flats to determine the position of the slide and roller with relation to each other, substantially as described.

20 14. In a carding-engine, the combination of 25 a chain of traveling flats, a flat grinding mechanism consisting of brackets secured to the engine-bend, a grinding-roll journaled in said brackets between the flats of the chain, a slide or frame to guide the flats to the roller, and a lever having an arm which is engaged by the traveling flats, whereby it is operated automatically to regulate the distance between the guiding-surface of the slide and the 30 face of the roller, substantially as described.

15. In an apparatus for grinding the flats

of a traveling chain for carding-engines, the combination of the brackets secured to the engine-bend, a grinding-roller journaled therein, the sliding frames *e*, carried by the brackets above the roller, and the levers fulcrumed on the brackets and engaging with the said sliding frames to regulate the distance between the surface of the roller and the supporting-faces of the frames *e*, substantially as 40 set forth.

16. In a carding-engine, the combination of 45 a chain of traveling reversible flats, a grinding mechanism consisting of a roller mounted between the upper and lower flats of the chain, a slide adjustable in guides of the roller-supporting bracket, a catch, as *f*, to reverse the flats as they reach the slide, and a lever pivoted on the bracket and actuated by the traveling flats to adjust the position of the 50 slide with relation to the roller, substantially as described.

In witness whereof we have hereunto set our hands in presence of two witnesses.
